UNITED STATES PATENT OFFICE

2,554,396

BUILDING CONSTRUCTION

Ellsworth D. Bloye, Hot Sulphur Springs, Colo.

Application November 23, 1949, Serial No. 129,147

10 Claims. (Cl. 72—1)

1

In its broadest aspect, the present invention relates to building construction, and in its more specific aspect to a joint assembly between the building wall and the roof structure.

The invention is directed to means for providing a weather-resistant structure from the outer wall to the inner wall between the wall and the roof and thereby effect a weather-proof joint, so to speak, between a cinder block wall and the wooden construction at the eaves, and the inventive concept may be employed with any type pitched roof and with any width rafters or joists.

It has always been a rather serious and difficult problem to achieve a weather-resistant construction between the building wall and the roof, and I have overcome this problem by the use of a plurality of specially constructed blocks which cooperate with the building wall, the pole plate, the joists and the rafters, in such a manner as to form a seal extending from the outer face to the inner face of the wall and between the joists and rafters.

An important object of my invention is to provide a roof structure wherein the building will be effectively sealed between the wall and the roof at the eaves.

A further object of the invention is to provide a novel building structure at the juncture of the building wall and the roof which can be built by unskilled labor in a minimum of time, the essential elements, namely the structural blocks being capable of being cheaply and quickly manufactured.

Another object is to provide a plurality of structural blocks which when laid cooperate with the building wall and the salient structural elements of the roof to give added support to the structural elements and at the same time prevent the climatic elements from entering the interior of the building at the juncture of the roof with the wall.

And a further object of my invention is to provide a building block which may be modified for employment either with a joist or a rafter or stud.

With the foregoing and other objects in view, the invention consists in the details of construction, and in the arrangement and combination of parts to be hereinafter more fully set forth and claimed.

In describing the invention in detail, reference will be had to the accompanying drawings forming part of this application, wherein like characters denote corresponding parts in the several views, and in which:

2

Figure 1 is a view in perspective of a building wall showing the manner in which the blocks are disposed, there being but a single rafter and joist shown.

5 Figure 2 is an elevational view looking from the inside of the wall and partly broken away.

Figures 3 and 4 are sectional views taken along the lines 3—3 and 4—4, respectively, of Figure 2.

10 Figure 5 is a top view, partly broken away, of the wall.

Figure 6 is an elevational view looking from the outside of the wall, the roof being partly broken away, and

15 Figures 7 to 10, inclusive are perspective views of the individual blocks.

Referring to the drawings, I have indicated a conventional cinder block wall 10, 11 denotes the upper face of the wall, a pole plate 12, rafters 13, joists 14, and structural blocks denoted generally 15.

20 The blocks 15 are preferably of the cinder block type, although, of course, it is obvious that other materials may be employed, depending upon the particular building specifications involved.

25 In order to effect the desired seal between the outer and inner faces of the wall 10, as well as the roof, I employ three types of blocks 15, designated 15A, 15B and 15C, which may be termed "a joist and gable eave block," "a rafter eave block," and

30 "a filler eave and gable block," respectively. The dimensions of the blocks 15A, 15B and 15C will vary in accordance with the size of the wall, the joists, the rafters and the pitch of the roof and, of course, a person skilled in building construction

35 can readily determine the particular dimensions necessary for the structure in question.

It can be seen that each of the blocks is basically the same, in that each block is approximately L-shaped. Referring first to the filler eave and

40 gable block 15C, it comprises a rear wall 16, a front wall 17 of considerably lesser height than the wall 16, side walls 18, top wall 19 and lower wall 20. The top wall 19 is inclined downwardly adjacent its juncture with the front wall 17, as shown at 21, the purpose of which is thought to be readily apparent.

45 The salient distinction between the block 15B and the block 15C resides in the fact that the rear wall 16B is formed with an extension 22, and it will be noted that the extension is of somewhat less height than the wall 16B. The extension 22 is approximately square in cross section, and the upper face of the extension is inclined downwardly, as shown at 23, for

50 cooperating with the rafter 13 associated therewith, as will later be more fully discussed.

The block 15A is substantially the same as the block 15C and the rear wall 16A is extended, as indicated at 24, and the upper face of the extension which is similar in cross section to that of the extension 22 is flat, as designated at 25, and the upper face terminates a substantial distance below the top wall 19A. The extension 24 will extend beneath the joist, for a purpose to be more fully set forth.

Hence, it can be seen that the extensions 22 and 24 on the block 15B and 15A, respectively, extend from opposite sides of the blocks; while I prefer the employment of the blocks 15A and 15B, it is possible to provide unitary blocks which may be used for either side of a building. This may be accomplished by molding the blocks with extensions 22 for 15B and 24 for 15A, respectively from the opposite sides thereof and forming a weakened or serrated portion at the point where the extension merges with the rear walls and the side walls. Hence, the blocks being used on either side of a building, that ear or extension not being employed may be struck with a suitable tool whereby the extension will be broken away from the block, and the remaining extension may be employed. I also find it advantageous to divide the block 15C into three equal parts by virtue of the weakened areas so that the width of the block may be altered to provide a proper fit.

In using the blocks to provide the weather-proof section, the pole plate or plates 12 extend the full length of the wall 10 and the outer face of the plate is flush with the outer face of the wall. The plate 12 is of lesser width than the wall 10 to provide a ledge, so to speak, upon which the rear wall of the blocks may rest, as clearly indicated in the drawings. As hereinabove mentioned the dimensions of the blocks will, of course, vary for the particular job being performed, but in the case of a roof structure wherein the rafters are fixed at 16 inch centers, I find that the use of one joist block and one rafter block will effectively accomplish the desired end. The block 15A is disposed with wall 16A resting upon the ledge formed by the wall 10 and the plate 12, and the lower face of the bottom wall 20A will then be in facial contact with the upper face of the plate. The extension 24 is then disposed beneath the joist 14 and the side wall brought into abutting relationship with the side of the joist. The block 15B will then be disposed adjacent to the block 15A with its side wall in engagement with the side wall of the block 15A, and the extension 22 will extend beneath the rafter 13 and the rafter will rest upon the inclined face 23. Of course mortar is applied to the blocks intermediate the ledge and the block, as well as between the abutting side walls of the blocks 15A and 15B. Additionally, extensions 22 and 24 will be bound beneath the joist and rafter, and it will be appreciated, therefore, that I provide a structure which is very stable at the location where the wooden roof construction and the top of the wall meet. The front wall of the blocks extends to the front of the wall 10 and, as the result, the wall is completely sealed against the elements between the outer face of the wall and the inner face thereof.

In the event the distance between the rafter centers is such that the use of the joist and rafter blocks will not close the area, one or more of the filler blocks 15C may be employed intermediate the blocks 15A and 15B.

It might be mentioned that all gables may be effectively sealed by the employment of one block

15A and a sufficient number of the filler blocks 15C to extend between the studs.

It will be appreciated, therefore, from the above description that I have provided an excellent assembly for accomplishing a weather-resistant seal from the outer surface to the inner surface of the building wall intermediate the wall and the roof structure, and by virtue of the simplicity of the structural elements employed, the seal may be readily and easily achieved by inexperienced workmen. Not only do the structural blocks seal the wall at the juncture of the wall and the eaves, but these blocks also give added support to the rafters and the joists. Additionally, the structural blocks will provide a substantially fireproof eave, thereby insuring no burning of old wooden blocking and causing a draft. Furthermore, in connection with plastering of the building, it can be seen that mason is assured of a full tie or bond on the building wall adjacent to the ceiling.

The invention is not to be confined to any strict conformity with the showing in the drawing, but may be changed or modified so long as such changes or modifications mark no material departure from the salient features of the invention as expressed in the appended claims.

I claim:

1. In a roof construction of the type wherein the joists and rafters are supported on a pole plate carried by the top of the building wall, a plurality of blocks disposed on the top of the wall and the plate intermediate the joists and rafters, there being a sufficient number of blocks to close the gap between adjacent joists and rafters, each of said blocks being of such dimensions as to extend from the front face of the wall to the rear face of the wall, and means to bind the blocks to the wall and adjacent blocks together.

2. A roof construction as claimed in claim 1 wherein the block adjacent the joist is provided with an extension adapted to be located beneath the joist, and the block adjacent the rafter being provided with an extrusion disposed beneath the rafter.

3. In a roof construction of the type wherein the joists and rafters are supported by a pole plate of lesser width than the top of the building wall, a plurality of building blocks of substantially L-shape disposed with the long leg resting on the pole plate and the short leg resting on the top of the wall intermediate the pole plate and the free end of the wall, each of said L-shaped blocks being of such dimensions as to extend from the rear face of the wall to the front face of the wall and there being a sufficient number of blocks to close the gap between adjacent joists and rafters, means to bind the short leg of each block to the wall, and further means to bind adjacent blocks together.

4. A roof construction as claimed in claim 3 wherein the block adjacent the joist is provided with an extension adapted to project beneath the joist, and the block adjacent the rafter having an extension adapted to be located beneath the rafter.

5. A roof construction as claimed in claim 4 wherein the extension projecting beneath the joist and the extension located beneath the rafter are bound together.

6. In a roof construction of the type wherein the joists and rafters are supported on a pole plate carried by the top of the building wall, sealing means supported by the pole plate and closing the space between adjacent rafters and

joists and extending from the front face of the wall to the rear face of the wall, and means securing the sealing means to the wall.

7. A building block for use with roof rafters comprising a substantially L-shaped body, an extension on the short leg of the body of less height than the short leg, and an inclined face on the extension adapted to be located under the rafter.

8. A block as claimed in claim 7 wherein the long leg is provided with an inclined face at its free edge.

9. A building block for use with roof joists comprising an L-shaped body, and an extension on the short leg of the body of considerably less height than the short leg adapted to be disposed beneath the joist.

10. A building block for use with roof rafters and/or joists comprising an L-shaped body, an

extension on the short leg of the body of slightly less height than the short leg, an inclined face on said extension and an extension on the opposite edge of said short leg of lesser height than the first named extension, and weakened areas at the point of juncture of each extension with the short leg whereby one or both of said extensions may be removed from the body.
